UNITED STATES PATENT OFFICE.

FRED S. CARR, OF BROOKLINE, MASSACHUSETTS, ASSIGNOR TO CARR FASTENER COMPANY, OF CAMBRIDGE, MASSACHUSETTS, A CORPORATION OF MAINE.

TURN-BUTTON FASTENER.

1,253,350.

Specification of Letters Patent. Patented Jan. 15, 1918.

Application filed May 7, 1917. Serial No. 166,342.

To all whom it may concern:

Be it known that I, FRED S. CARR, a citizen of the United States, residing at Brookline, in the county of Norfolk and State of Massachusetts, have invented new and useful Improvements in Turn-Button Fasteners, of which the following is a specification.

This invention relates to a fastener for carriage curtains and the like, comprising a shank adapted to be attached to a rigid support such as the body of a vehicle or the member of frame of a vehicle top, or to a flexible support such as a sheet forming a part of a top or cover, and formed to enter a buttonhole or eyelet in a curtain or cover portion, and an oblong button pivoted to the shank and formed to register with and freely enter a buttonhole when turned to one position, and to be turned crosswise of the buttonhole to overhang portions of the margin thereof and confine the curtain or cover portion against removal from the shank. The shank is usually of oblong form corresponding to that of the buttonhole and button.

Fasteners of this character, known as turn-button fasteners, are provided with means for yieldingly confining the button either in registration with the shank, or crosswise thereof, so that the button will remain in either position until forcibly turned therefrom.

The invention is embodied in a turn-button fastener in which the shank and its attaching base are made in a single sheet metal piece or part, and are adapted to coöperate in yieldingly confining the button in either of the described positions without the employment of retaining devices supplemental to the shank and formed separately therefrom.

Of the accompanying drawings forming a part of this specification,—

Figure 1 is a perspective view of a turn-button fastener embodying the invention, the button being separated from the shank.

Fig. 2 is a sectional view showing the shank and button connected.

Fig. 3 is a view similar to Fig. 2, showing the button differently constructed.

Fig. 4 is a sectional view of the button shown by Fig. 3, before its engagement with the shank.

Fig. 5 is a plan view of the fastener show-

ing the button turned to position to open 55 the shank jaws hereinafter described.

Fig. 6 is a plan view, showing the button in its operative position and confined by the jaws.

Fig. 7 is a perspective sectional view of 60 the shank and its attaching base.

Fig. 8 is a view similar to Fig. 6, showing a modification.

Fig. 9 is a fragmentary perspective view, 65 showing another modification.

The same reference characters indicate the same parts in all the figures.

The hollow shank 12 and the attaching base 13 of my improved fastener are made from a single blank of sheet metal, converted by a series of operations into the form shown by the drawings, the base being continuous and surrounding the inner end of the shank. The margin of the base has a downwardly projecting flange formed to 70 bear on a support. The top portion of the base may be provided with screw-receiving orifices preferably bounded by tapering flanges 14. In case the shank is not attached to a carrying part by screws, the base may 75 be provided with attaching prongs 14^a, as indicated by Fig. 9.

The hollow shank is divided by slots 15 into two sections, each including practically one-half of the wall of the shank and one-half of the closed outer end or head of the shank, said head therefore including two separable head portions 12^a, which are normally held yieldingly in contact with, or in close proximity to each other by the continuous resilient base 13.

The head portions 12^a are recessed to form coinciding jaws 16, said jaws collectively forming the wall of an expandible socket, adapted to receive a stud 17 projecting 95 downwardly from the under side of a button 18, the jaws yieldingly embracing the stud and being adapted to confine the stud and button in different positions. To give said jaws a wide bearing on the stud 17, I 100 preferably form them by turning parts of the head portions 12^a inwardly, thus forming lips or flanges as shown clearly by Figs. 1 and 7.

In the embodiment of the invention shown by Figs. 1, 5, 6 and 7, the said jaws and stud are of angular form, the jaws preferably forming an angular socket, and the

stud being preferably rectangular in cross section. There is, therefore, a yielding interlocking engagement between the button and shank, not only when the button is turned to position to register with the stud and enter a buttonhole therewith, but also when the button is turned so that its major axis is at right angles with the major axis of the stud, as shown by Fig. 6. When the button is turned to an intermediate position the stud 17 forces the head portions apart, as shown by Fig. 5, the jaws being permitted to close when the button and stud are turned to registering position and to the position shown by Fig. 6.

The jaws and stud may be formed to hold the button in different positions wholly by friction and without the above-described yielding interlocking engagement, as shown by Fig. 8, in which the jaws 16^a are semi-circular, and the stud 17^a is circular in cross section. In this modification the diameter of the stud is preferably greater than the normal diameter of the space bounded by the jaws, so that the insertion of the stud between the jaws increases the width of the slots 15, the jaws being therefore caused to exert a constant uniform pressure on the stud.

The button and stud may be hollow and made of sheet metal as shown by Figs. 1 and 2, or may be solid as shown by Figs. 3 and 4. The stud is formed to project below the jaws and is upset at its inner end to engage the lower edges of the jaws, as

shown by Figs. 2 and 3, the button being thus secured to the shank.

The continuous resilient base 13 constitutes an effective spring member maintaining the shank jaws in yielding engagement 40 with the button stud.

I claim:

1. A turn-button fastener comprising a hollow sheet metal shank, a continuous sheet metal base integral with and surrounding the inner end of the shank, and adapted to be attached to a support, said shank being divided into separable sections which are connected by the base, said sections having head portions provided with coinciding recesses, the walls of which constitute separable jaws which are normally closed by the resilience of the base, and a button having a stud yieldingly engaged by and adapted to rotate between said jaws.

2. A turn-button fastener as specified by claim 1, the said jaws being formed by flanges integral with and turned inwardly from said head portions, and presenting relatively wide faces contacting with said stud.

3. A turn-button fastener as specified by claim 1, said jaws and stud being angular to cause an interlocking engagement therebetween, and the stud being formed to alternately separate and permit the closing of the jaws.

In testimony whereof I have affixed my signature.

FRED S. CARR.
